UNITED STATES PATENT OFFICE.

WILLIS ADKINS, OF WILLIS, TEXAS, ASSIGNOR OF ONE-HALF TO A. M. CARSON, OF WILLIS, TEXAS.

COTTON-PICKER.

No. 849,182.

Specification of Letters Patent.

Patented April 2, 1907.

Application filed April 17, 1906. Serial No. 312,149.

To all whom it may concern:

Be it known that I, WILLIS ADKINS, a citizen of the United States, residing at Willis, in the county of Montgomery and State of Texas, 5 have invented new and useful Improvements in Cotton-Pickers, of which the following is a specification.

This invention relates to cotton-pickers, the object of the invention being to provide a 10 simple and efficient hand device for facilitating the picking of cotton and one which will be agreeable to the user, the device being in the form of a skeleton glove, which is open at the front and back of the hand and which 15 is therefore cool and sanitary in excessively hot weather. The several parts of the device are also adjustable relatively to each other, so as to adapt the device as a whole to hands of different sizes.

20 With the above and other objects in view the invention consists in the novel construction, combination, and arrangement of parts, hereinafter more fully described, illustrated, and claimed.

25 In the accompanying drawings, Figure 1 is a plan view of the cotton-picking device shown applied to the left hand looking toward the back of the hand. Fig. 2 is a detail plan view of a portion of the device, showing 30 the adjustment of the several parts. Fig. 3 is a detail view of one of the thimbles or finger stalls.

The cotton-picking device contemplated in this invention comprises, essentially, a plurality of thimbles or finger-stalls 1, one of 35 such thimbles or stalls being provided for each of the fingers and the thumb. Each thimble or stall is of cylindrical and slightly-tapering form, so as to fit neatly and snugly over the 40 end of the finger and thumb, as the case may be, and may be made of metal or leather or any suitable material, but is preferably made of metal and provided on that side which covers the inner portion of each finger 45 or thumb with a laterally-projecting gripping-lip 2, the arrangement being such that when all of the finger-stalls are brought together in a group by the fingers the gripping-lips will obtain a firm and positive hold on the 50 cotton without chafing or rubbing the finger tips, the latter being thoroughly protected by the thimbles or stalls.

Each of the thimbles 1 is stitched or otherwise secured, as shown at 3, to the outer extremity of a thimble-strap 4, one strap being 55 used for each thimble. The straps 4 all extend backward to a wrist-strap 5, being adjustably connected thereto by means of buckles 6, whereby the straps 4 may be lengthened or shortened to agree with the 60 lengths of the fingers and thumb of the operator. The wrist-strap 5 is also provided with a buckle 7, whereby it may be fastened with any desired degree of tightness around the wrist of the operator. The thimble- 65 straps 4 are further connected at the proper distance apart by a tie-strap 8, which extends across the backs of all of the straps 4, as shown in Fig. 1. A palm strap or loop 9 is also connected with all of the thimble-straps 70 4, being secured to the inner sides of said straps and adapted to be slipped over the fingers so as to embrace the main body of the hand and extend across the palm thereof, as clearly indicated in Fig. 1. It will thus be seen that 75 the cotton-picking device is easily applied to the hand and secured thereon and that the individual thimbles or finger-stalls are adjustable relatively to the wristband, so that said thimbles or stalls may be brought to the desired relative position to fit over and be retained securely upon the finger-tips and the end of the thumb.

I claim—

The herein-described cotton-picking device consisting of a skeleton glove provided with a thimble for each finger and the thumb, said thimbles each having a laterally-projecting gripping-lip, a wrist-strap, a strap connected with each thimble and extending to the 90 wrist-strap, buckles on the wrist-strap for adjusting the thimble-straps independently, and a tie-strap extending across the thimble-straps and connected thereto, essentially as described.

95 In testimony whereof I affix my signature in presence of two witnesses.

WILLIS ADKINS.
